UNITED STATES PATENT OFFICE.

WILLIAM GORMAN, OF NEW BRITAIN, CONNECTICUT, ASSIGNOR TO THE
RUSSELL AND ERWIN MANUFACTURING COMPANY, OF SAME PLACE.

DESIGN FOR A KEY-HOLE ESCUTCHEON.

Specification forming part of Design No. 7,021, dated December 9, 1873; application filed November 15, 1873.
[Term of Patent 14 years.]

To all whom it may concern:

Be it known that I, WILLIAM GORMAN, of New Britain, in the county of Hartford and State of Connecticut, have invented a new Design for a Key-Hole Escutcheon; and I do hereby declare that the following specification, taken in connection with the drawings making a part of the same, is a full, clear, and exact description thereof.

Figure 1 is a front view, and Fig. 2 a top edge view, of said escutcheon design.

The outline, which is one distinguishing feature of my said design, is that of an armorial shield. A border, B, corresponding with said outline, except at the top, where it meets in two scrolls, C C, is another feature. From said scrolls depends a banner, D, which forms a field or border around the key-hole, and from

which depends the trefoil J at the bottom, and scrolls or leaf-work s from the top of said banner on each side, between it and the border.

The said trefoil and the scroll and leaf-work I do not consider as essentially a part of my design; but these may be changed or omitted, the characteristic features of said design being the outline of an armorial shield, with the border B and banner D at the key-hole.

What I claim as my invention, and desire to secure by Letters Patent, is—

The design for a key-hole escutcheon, substantially as herein shown and described.

WILLIAM GORMAN.
